(No Model.)

A. B. BIRD.

LIFE INSURANCE POLICY.

No. 408,686.

Patented Aug. 13, 1889.

No. 181. Check Endowment.

In Consideration of the representations and declarations made in the application for this Policy, which is hereby made part of this contract, and of the payment of an annual Premium of Twelve and 300/100 Dollars, or in semi-annual instalments of Six and 300/100 Dollars, or in quarterly instalments of Three and 300/100 Dollars, to be paid on or before the 1st day of May in each year, for the term of Forty-five years, Does hereby ensure the life of A. B. BIRD, of C. - - - - - O - - - - -, and State of New York, in the sum of One thousand Dollars, the said sum being payable at the home office of this Company, to Mrs. J. M. BIRD, in twenty equal instalments of Fifty Dollars, as witnessed by the checks hereto attached, or if said insured survive said beneficiary, to his legal representatives, in twenty equal annual instalments of Fifty Dollars, as witnessed by the checks hereto attached, upon receipt of satisfactory proof of the death of said insured, during the continuance of this Policy (less the balance of any partially paid annual Premiums, or other indebtedness, of the insured or beneficiary to this Company). And in the event of the said A. B. BIRD, surviving the age of Fifty years, the said sum of One Thousand Dollars, will be paid to said insured in Twenty, equal annual instalments of Fifty Dollars, as witnessed by the checks hereto attached; or on the event of the death of the insured prior to the maturity of any or all of the checks hereto attached, the remaining checks will be paid as they mature, according to the terms and conditions of said checks.

All premiums are payable at the Home Office of this Company at H, but may also be paid to any duly authorized agent of said Company upon his giving proper receipt signed by the President or Secretary of said Company.

This Policy shall not take effect unless the first premium is paid while the assured is in good health, and in case the second annual premium is not paid when due, this Policy, and all claims under it shall be void, and the premiums already paid forfeited to this Company.

In case of default in payment of any annual premium after the second, this Policy will remain in full force for the term specified in this table of paid-up term in insurance:

UNITED STATES PATENT OFFICE.

ALEXANDER B. BIRD, OF CANANDAIGUA, NEW YORK.

LIFE-INSURANCE POLICY.

SPECIFICATION forming part of Letters Patent No. 408,686, dated August 13, 1889.

Application filed July 2, 1888. Serial No. 278,873. (No specimens.)

To all whom it may concern:

Be it known that I, ALEXANDER B. BIRD, of Canandaigua, county of Ontario, in the State of New York, a citizen of the United States, 5 have invented certain new and useful Improvements in Life-Insurance Policies, of which the following is a specification, reference being had to the accompanying drawing.

This invention relates to policies issued to insure life.

The object of this invention is to provide the policy with certain tabulated statements of utility both to the insurer and to the insured.

15 It consists in the several novel features of construction hereinafter described, and which are specifically set forth in the clauses of claim hereunto annexed.

The drawing accompanying this specification sets forth a substantial copy of the policy provided with all of the tabulated statements which can be of benefit to the insured, and which must necessarily vary with the age of the insured according to the rules laid down

20 by life-insurance actuaries, which are based upon the mortality tables. Accordingly this drawing illustrates the principle of the invention only, because the figures in the tabulated statements must vary with the amount 25 of the policy and with the ages of the insured.

A represents the body of the policy, which may be of any form of wording desired to bring it within the category of either a straight 35 life, a plane endowment, a term endowment, a check endowment, or any of the other numerous styles of premium or assessment policies.

B is a band extending across the face of the 40 policy, having a line B' extending longitudinally thereof, forming upper and lower compartments B² and B³, respectively subdivided by vertical lines B⁴ into rectangular or oblong compartments B⁵ and quadrangular or square 45 compartments B⁶. The latter compartments are further divided by diagonal lines B⁷. On this band is a tabulated statement showing the term for which the policy will remain in full force after a default has been made in the 50 payment of an annual premium. The upper horizontal line of numbers in the compart-

ments B⁵ indicates the numerically successive years of the policy. The lower series of diagonally-divided compartments indicate the number of years and months, or the term, during which the policy will so remain in full force without any further payment of premiums—as, for instance, if at the end of the second year a failure is made to pay the premium for the third year, the policy, as indicated by 55 the figures in the compartments below 2, will remain in full force for the term of one year and seven months, and that in case of a failure to pay the premium due at the end of the ninth year the policy will remain in force for the 60 term of six years, and that in case of a failure to pay the premium due at the end of the nineteenth year the policy will remain in force for the further term of twelve years and eight months without any further premium being 65 paid. It will therefore be observed that from this tabulated statement the insured can always tell from his policy just how long his insurance will hold good if he fails to pay any premium when due.

At C, I show a similar band to that B, having a tabulated statement showing in the upper half of the diagonally-divided compartments the numbers of the successive years of the policy for which it is to run, and in the lower half of these compartments the amount for which a paid-up policy will be issued by the company to the insured in case of his default in making payments of any premium when due. It will therefore be seen from 80 this table that if at the end of the second year the insured fails to pay the premium due to renew the policy or to keep it alive for the third year a paid-up policy will be issued to him for the sum of fifty-three dollars; that 85 in case of a failure at the end of the ninth year a paid-up policy will be issued for two hundred and seven dollars, and that in case of a failure to pay the premium due at the end of the nineteenth year a paid-up policy 90 will be issued for four hundred and thirty-nine dollars.

At D, I show another band similar to that B, having a table of cash-surrender values, in which I show in the upper half of the diagonally-divided compartments the successive 95 serial years of the term of the policy, and in

the lower half of these compartments I show the actual amount of cash which would be received by the insured upon surrender of his policy at the end of any year—as, for instance, if he surrendered it at the end of the second year or during that year he would receive in cash the sum of five dollars, or if he surrendered it during the ninth year he would receive forty dollars, or if he surrendered it at the end of the nineteenth year he would receive one hundred dollars. It will therefore be observed that a person holding this policy for one thousand dollars, the annual premium being twelve dollars and fifty cents, can readily perceive from the face of his policy that in case he failed or defaulted in the payment of the premium due at the end of the second year his policy would continue in force for the term of one year and seven months without any additional premium; or that if he desired he could receive a paid-up policy for fifty-three dollars, or that if he chose to surrender his policy he would receive the sum of five dollars in cash; also, that if at the end of the ninth year he made default in the payment of the premium then due his policy would stand good for six years longer without the payment of any further premium, that he could surrender and take a paid-up policy at that time for two hundred and seven dollars, or that he could give up his policy and receive the sum of forty dollars in cash therefor, and so on. It will also appear that, as some insurance companies are conducted upon such a basis that they will allow no paid-up-term insurance after a default in the making of a payment of premium when due, the first table B would then be unnecessary in that policy. In like manner some companies provide for a paid-up-term insurance and for a paid-up policy to be issued upon default in the payment of a premium,

in which case the table D would not be incorporated into the policy. In like manner some companies provide for paid-up term and cash-surrender value, in which case the table C would not be necessary. I do not therefore restrict myself to the use of all three of these tables in a policy, for the reason that in some policies only one may be necessary, some may require two of the tables, and some will require all three. It will be further observed that the policy here shown is a check endowment providing for the payment to the insured of twenty equal installments of fifty dollars each, annually; and that at E, upon the bottom of the policy, I show the form of checks for each annual installment of principal, which checks are disposed across the bottom of the policy. 60

What I claim as my invention, and desire to secure by Letters Patent, is—

1. A life-insurance policy having a band B extending across the face thereof, provided with a longitudinal dividing-line B', forming upper compartment B² and lower compartment B³, subdivided by vertical lines B⁴ into oblong compartments B⁵ and square compartments B⁶, substantially as described. 65

2. A life-insurance policy having a band B extending across the face thereof, provided with a longitudinal dividing-line B', forming upper compartment B² and lower compartment B³, subdivided by vertical lines B⁴ into oblong compartments B⁵ and square compartments B⁶, having diagonal lines B⁷, substantially as described. 70

In witness whereof I have hereunto set my hand this 3d day of June, 1888.

ALEXANDER B. BIRD.

In presence of—

JOHN S. TAGGART,
GEORGE ROBINSON.
